H. LEONI

NECKTIE

Filed March 2, 1927

FIG. 1

FIG. 2

FIG. 3

FIG. 4

Hugo Leoni,

INVENTOR

BY
Robert B. Killgore
ATTORNEY

UNITED STATES PATENT OFFICE.

HUGO LEONI, OF NEW YORK, N. Y.

NECKTIE.

Application filed March 2, 1927. Serial No. 172,053.

My invention relates to improvements in neck ties and it is my object to produce a neck tie which will have a lengthwise stretch in sliding through the collar and in tying and which will contract into its original length in snug condition and in which the folds and creases produced by tying and untying will be reduced to a minimum.

In the drawing Fig. 1 is a plan view, with the facing removed, of my improved tie, the center part being broken away for convenience in illustration; Fig. 2 is an exaggerated longitudinal sectional view of the structure of Fig. 1 on the line 2—2 thereof; Fig. 3 a sectional view of the structure of Fig. 1 on the line 3—3 thereof; and Fig. 4 a sectional view of the structure of Fig. 1 on the line 4—4 thereof.

My invention relates primarily to hand made ties as distinguished from those which are machine made but I do not limit myself thereto. Such ties consist of a body portion which is generally cut on the bias so that it will have a slight lengthwise stretch and a lining sewed inside the body portion by hand. Heretofore the lining has generally been of non-stretchable material and has been firmly united to the body so that in pulling the tie through a collar in tying and untying it the give of the body is opposed to the non-stretch of the lining and the line of stitching uniting the two has frequently broken.

If a rubber lining is sewed into the tie in the ordinary way the tie will not have any lengthwise stretch unless the stitches break, as the pull is resisted and the stretch is resisted by the unyielding line of stitching. If a rubber lining is loosely inserted in the tie without attachment to the fabric the fabric will stretch and slide on the loose rubber lining and will not have the assistance of the rubber to return it to its original length.

My invention enables me to use a rubber lining with its attendant advantages and permits the body of the tie and the lining to stretch and contract together due to the use of a perforated rubber lining through the perforations of which the stitches pass.

In my improved tie the body 1 is made of any suitable material and is preferably cut on the bias. The lining 2 is a piece of sheet rubber cut to the general contour of the finished tie and is provided with a plurality of perforations 3 suitably arranged lengthwise of the lining. These perforations are formed in advance of sewing the tie together and are preferably punched to leave rough edges for a purpose hereinafter set forth. The perforations are sufficiently large to perform their functions as herein-after described. This rubber lining extends the entire length of the tie.

A tie embodying my invention has the body folded edge-wise on itself as shown in Figs. 3 and 4 with an outer face 4 and seamed back 5—6, the edge of the ply 5 being turned back on itself at 7 and then over the ply 6 at 8, with the rubber lining 2 enclosed in the flat tube so formed. A line of stitches 9 passes through the perforations 3 and the plies 6, 7 and 8 but are not pulled tight. This unites the edges of the body of the tie and secures the rubber lining in place. If the perforations are left with rough edges the operator, in making the tie, has no trouble in locating them by feeling to pass the needle through them in sewing by hand. The perforations, being relatively large in comparison to the thread used, the rubber lining is not confined or constricted by the stitches and is free to yield with the body of the tie without imposing a strain on the stitches.

By this construction the rubber lining is concealed inside the tie and the tie may stretch slightly over its entire length and return to its initial condition due to the elasticity of the rubber lining, the fact that the body is cut on the bias and the fact that the stitches are not drawn tightly. The rubber, being resilient, will always assume a flat condition after a knot has been untied and will reduce the effects of folding and creasing of the body to a minimum in contrast to the results of wrinkling and creasing a fabric lined tie.

I am aware of the fact that rubber linings have heretofore been used in neck ties and

my invention relates chiefly to hand made ties which have a limited stretch over their entire length.

I claim:—

5 A necktie comprising a tubular body portion stretchable lengthwise; a rubber lining provided with a plurality of perforations, said perforations being of relatively large size with respect to the stitching passing

therethrough, extending the length thereof; 10 and a line of stitches extending through the perforations and engaging the body, said stitches being loosely drawn, whereby the tie may elongate and return to its initial condition.

15 In testimony whereof I have affixed my signature.

HUGO LEONI.
